UNITED STATES PATENT OFFICE

JOSEPH BERGER, OF UTICA, NEW YORK, ASSIGNOR TO UNION SPECIAL MACHINE COMPANY, OF CHICAGO, ILLINOIS, A CORPORATION OF ILLINOIS

THREAD CONTROLLING MECHANISM FOR SEWING MACHINES

Application filed May 31, 1928. Serial No. 281,878.

The invention relates to new and useful improvements in thread controlling mechanisms for sewing machines, and more particularly to a thread controlling mechanism having a rotating controller with a laterally projecting thread engaging surface overhanging the axis of rotation of said member.

An object of the invention is to provide a thread controlling mechanism of the above type having thread guides, one of which is located within the path of rotation of said projecting surface and the other of which is located without said path of rotation, with means for supporting said thread guides whereby the same may be shifted circumferentially about the axis of rotation of the controlling member.

A further object of the invention is to provide a thread controlling mechanism of the above type wherein the inner thread guide is shiftable longitudinally of the axis of rotation of the thread controlling element for rendering the same accessible for threading.

A further object of the invention is to provide a thread controlling mechanism of the above type having thread guides which are shiftable circumferentially about the axis of rotation of the thread controlling member wherein a thread retainer and a thread cast-off are associated with the controlling member and mounted for circumferential adjustment about the axis of rotation of the controller.

These and other objects will in part be obvious and will in part be hereinafter more fully disclosed.

In the drawings which show by way of illustration one embodiment of the invention:

Fig. 1 is a plan view of a portion of a sewing machine having the thread controlling mechanism embodied therein.

Fig. 2 is an enlarged view partly in side elevation and partly in section showing the thread controller.

Fig. 3 is a sectional view on the line 3—3 of Fig. 2.

Fig. 4 is a plan view of a portion of the thread controlling mechanism showing the

inner thread guide moved to position for threading.

Fig. 5 is a sectional view on the line 5—5 of Fig. 3.

Fig. 6 is an enlarged detail in perspective of the outer thread guide.

The invention is directed to a thread controlling mechanism for sewing machines of the type wherein the thread controlling element is mounted for rotation. The thread controlling element is provided with a cylindrical peripheral projecting flange which extends laterally from the supporting member therefor so as to overhang the axis of rotation of the member. The free edge of this cylindrical projection is cam-shaped and is the active element which moves the thread for taking up and giving up the thread during the stitch formation. Associated with the thread controlling cam are thread guides, one of which is located within the peripheral flange and the other of which is outside of the peripheral flange, so that the thread running from one thread guide to the other is positioned so as to be engaged by the projecting cams on the controlling member. These thread guides are both mounted on a collar carried by a stationary sleeve located coaxially with the axis of rotation of the thread controlling member. This collar is capable of being adjusted about the sleeve and thus provides means for circumferentially adjusting the thread guides about the axis of the thread controller, for positioning the thread guides in different set positions. The inner thread guide is mounted on said collar so that it can be swung outwardly from beneath the projecting flange of the thread controlling element for threading and means is provided for yieldingly holding the thread guide in normal operating position.

Also associated with this rotating thread controlling member is a cast-off and a retainer. The cast-off and retainer are mounted on a collar which is secured to this sleeve independently of the collar which carries the thread guides so that the cast-off and retainer may be adjusted circumferentially about the axis of rotation of the controlling member.

element without disturbing the set position of the thread guides.

Referring more in detail to the drawings, the invention is shown as applied to a sewing machine which includes a supporting frame 1 in which is mounted a rotating shaft 2, which in the present embodiment of the invention is the main actuating shaft, and from this main actuating shaft the various parts of the stitch forming mechanisms are operated. So far as the present invention is concerned, any rotating shaft in a sewing machine may be used as the actuating means for the improved thread controlling mechanism. Mounted on this shaft 2 is a thread controlling member 3. This thread controlling member 3 includes a hub portion 4 which is fixed to the shaft by a set screw 5. Extending outwardly from the hub portion is a disc 6. The disc 6 is provided with two laterally projecting cylindrical flanges 7 and 8. These flanges 7 and 8 are formed at different radial distances from the axis of the shaft and are spaced from each other as indicated in the drawings. The flanges are similarly shaped and each flange is provided with cut away portions so as to form projecting cams which engage the thread for taking up and releasing the same.

These flanges overhang the axis of rotation of the thread controlling member. Associated with the flanges is a thread guiding member 9 having, in the present embodiment of the invention, two thread guiding eyes 10, 10. The thread guiding eyes are located back from the outer surface of the member in which they are formed and said member is provided with narrow slots leading to the thread eyes so that the thread which is to be guided by the eyes may be inserted in the eye through said slot. Carried by the member 9 is a bar 11 underneath which the threads may be passed and this bar assists in retaining the threads in the eyes 10, 10. This thread guiding member is disposed outside of the thread controlling member and is positioned so as to be directly over the flange at all times. The thread guiding member 9 is mounted at the outer end of an arm 12. This arm 12 is secured to a collar 13. The arm projects outwardly in a direction substantially parallel with the axis of rotation of the thread controlling member to a point well beyond the thread controlling cams. The arm is bent so as to extend in a radial direction away from the axis of rotation and is then bent so as to extend in the general direction of the axis of rotation and support the thread guides in the manner stated above. This collar 13 on which the outer thread guide is mounted is a split collar having projecting ears through which a clamping screw 14 passes. This split collar is mounted on a sleeve 15 which surrounds the shaft 2. The sleeve 15 carries a housing 16 which is formed

integral therewith. This housing is held from rotation by means of a pin 17 carried by the frame of the machine and extending into a slot 18 formed in the housing. The housing is for the purpose of enclosing the operating cam for the nipper springs, which nipper springs are indicated at 19 in the drawings. This housing and related nipper springs form no part of the present invention, except as the housing holds the sleeve stationary on which the thread guides are mounted. Also associated with the thread controlling member is an inner thread guiding member 20. This inner thread guiding member 20 is provided with two thread eyes 21, 21, set back from the face of the thread guiding member and said thread guiding member is provided with slots leading to the thread eyes. This is for the purpose of rendering the inner thread guide self-threading. The thread guiding member 20 is provided with a projecting curved end 22. By laying the thread against the curved face of this projecting member, it may be moved along the curved face and through the slot into the thread guiding eye. The thread guiding member 20 is carried by an arm 23 which is pivoted at 24 to a lug 25 fixed to the collar 13 on which the outer thread guide is mounted. The arm 23 is provided with a laterally projecting portion 26 which carries a hand piece 27. This hand piece projects upwardly to a point where it is readily accessible to the operator through a suitable opening in the upper portion of the frame. The operator through the hand piece can swing the thread guiding member 20 about its pivotal support so as to position the thread guiding eyes 21, 21 well out from beneath the overhanging flanges 7 and 8, as shown in Fig. 4, and also in broken lines in Fig. 3. In this position the inner thread eyes can be readily threaded. The operator then by manipulating the hand piece 27 returns the thread guide 20 to its normal operating position as shown in full lines in Fig. 3.

Mounted on the collar 13 is a spring arm 28. Said arm 28 is secured to the sleeve by means of a clamping screw 29. The arm curves outwardly and is provided with a raised projection 30. This spring arm lies directly beneath the thread guide supporting arm 23. Said thread guide supporting arm has a recess 31 in its under face. When the parts are in normal position for operation the projection 30 engages this recess 31 and this will yieldingly hold the thread guide 20 in its operating position. Pressure on the hand piece 27 will swing the arm 23 about the pivot 24 and the projection 30 will pass off the edge of the arm 23 and hold the thread guide 20 yieldingly in position for threading the eyes therein.

From the above it will be noted that both the inner thread guide 20 and the outer thread

guide 9 are mounted on this split collar 13. By loosening the clamping screw 14 the collar may be shifted about the axis of rotation of the thread controlling member and thus the 5 thread guides circumferentially shifted relative to said axis. This provides for the shifting of the thread guides circumferentially about the axis of rotation of the thread controlling member and for securing said thread 10 guides in their various set positions.

Associated with the thread controlling member is a cast-off 32 and a retainer 33. The cast-off and retainer are both mounted on an arm 34 formed integral with a supporting collar 35 which is clamped to the sleeve 15 by means of a clamping screw 36. By loosening the clamping screw 36, the collar 35 may be shifted about the axis of rotation of the thread controlling member 15 and thus the retainer and cast-off shifted circumferentially and secured in different set positions. This collar carrying the cast-off and retainer can be adjusted independently of the collar for the thread guides 20 and likewise the collar for supporting the thread guides may be adjusted independently of the collar supporting the retainer and cast-off.

The thread passes from the supply 25 through suitable tensions, thence through the nipper springs 19. From the nipper springs, the thread passes to the inner thread guide and thence to the outer thread guide. Between the inner and outer thread guides the controlling cams move. The controlling cams will be brought into engagement with the thread and will carry the thread along with them until the cast-off engages the threads and casts them off from the projecting cams. 30 The retainer will retain the cast off threads giving the threads up slowly to the stitch forming elements. This particular type of thread controlling element with the cast-off, retainer, and inner and outer thread guides 35 forms no part of the present invention but is shown described and claimed in the application, Serial No. 715,421, filed May 23, 1924 by James R. Moffatt. The present invention, as noted above, has to do with the mounting of the thread guides and the cast-off and retainer. By shifting the thread guides circumferentially of the axis of rotation of the thread controlling element the time interval in the cycle of operation of the 40 machine at which the thread is engaged by the controlling cams is varied. Also by shifting the supporting collar for the cast-off the time interval in the cycle of operation at which the thread is cast from the controlling cam is varied. These adjustments are independent of each other and contribute to a nicety of adjustment of the thread controlling mechanism so as to insure a proper control of the threads. By 45 shifting these parts circumferentially of the

axis of rotation they may be adjusted and repositioned without varying their position radially relative to the axis of rotation and thus in a large measure the adjustments of these parts affect the timing of the operations without changing the character of the thread take up and giving up actions. Furthermore, it will be noted that both the inner and outer thread guides are mounted on the same split collar and, therefore, 70 when one is adjusted the other is adjusted with it, and inasmuch as the outer thread guide is further removed from the axis of rotation than the inner thread guide these guides when they are shifted from one set 75 position to another will always remain in the same relation to each other radially of the controlling element. While the thread controlling mechanism is shown as applied to a shaft intermediate the ends thereof it 80 will be understood that it may be applied at the end of the shaft as shown in the Moffatt application.

It is obvious that minor changes in the details of construction and arrangement of the parts may be made without departing from the spirit of the invention as set forth in the appended claims.

Having fully described my invention, what I claim as new and desire to secure by Letters 90 Patent, is:—

1. A thread controlling mechanism for sewing machines including a rotating thread controlling member having a laterally projecting thread engaging surface overhanging the axis of rotation of said member, thread guides located one within and the other without said overhanging portion, a support for said thread guides, and means whereby said support may be adjusted circumferentially about the axis of rotation of the controlling member for varying the set position of the thread guides.

2. A thread controlling mechanism for sewing machines including a rotating thread controlling member having a laterally projecting thread engaging surface overhanging the axis of rotation of said member, thread guides located one within and the other without said overhanging portion, a support for said thread guides, means whereby said support may be adjusted circumferentially about the axis of rotation of the controlling member for varying the set position of the thread guides, and means whereby the inner thread guide may be moved from beneath the overhanging portion for rendering the same accessible for threading.

3. A thread controlling mechanism for sewing machines including a rotating thread controlling member having a laterally projecting thread engaging surface overhanging the axis of rotation, thread guides located one within and the other without said overhanging portion, and means whereby said inner 100

thread guide can be moved longitudinally of the axis of rotation from beneath said overhanging portion to render the same accessible for threading.

5 4. A thread controlling mechanism for sewing machines including a rotating thread controlling member having a laterally projecting thread engaging surface overhanging the axis of rotation of said member, thread

10 guides located one within and the other without said overhanging portion, a support for said thread guides, means whereby said support may be adjusted circumferentially about the axis of rotation of the controlling member

15 for varying the set position of the thread guides, means whereby the inner thread guide may be moved from beneath the overhanging portion for rendering the same accessible for threading, and yielding means for holding 80

20 said inner thread guide in normal position beneath the overhanging portion.

5. A thread controlling mechanism for sewing machines including a rotating thread controlling member having a laterally projecting

25 thread engaging surface overhanging the axis of rotation, thread guides located one within and the other without said overhanging portion, means whereby said inner thread guide can be moved longitudinally of the axis

30 of rotation from beneath said overhanging portion to render the same accessible for threading, and yielding means for holding said inner thread guide in normal position beneath the overhanging portion.

35 6. A thread controlling mechanism for sewing machines including a rotating thread controlling member having a laterally projecting thread engaging surface overhanging the axis of rotation of said member, thread

40 guides located one within and the other without said overhanging portion means for supporting said thread guides, a cast-off and a retainer associated with said thread controlling member, and means for supporting said

45 cast-off and retainer whereby the same may be adjusted circumferentially about the axis of rotation to different set positions, said support for the thread guides and said support for the cast-off and retainer being independent of each other and capable of independent coaxial adjustments.

50 7. A thread controlling mechanism for sewing machines including a rotating thread controlling member having a laterally projecting

55 thread engaging surface overhanging the axis of rotation of said member, thread guides located one within and the other without said overhanging portion, a stationary member mounted coaxially with said controlling member, a split collar supporting said thread guides and mounted on said stationary member and adjustable circumferentially about the same.

60 8. A thread controlling mechanism for sewing machines including a rotating thread

controlling member having a laterally projecting thread engaging surface overhanging the axis of rotation of said member, thread guides located one within and the other without said overhanging portion, a stationary member mounted coaxially with said controlling member, a split collar supporting said thread guides and mounted on said stationary member and adjustable circumferentially about the same, said inner thread guide being pivotally supported on said collar whereby said thread guide may be swung from beneath the overhanging portion for threading.

70 9. A thread controlling mechanism for sewing machines including a rotating thread controlling member having a laterally projecting thread engaging surface overhanging the axis of rotation of said member, thread

75 guides located one within and the other without said overhanging portion, a stationary member mounted coaxially with said controlling member, a split collar supporting said

80 thread guides and mounted on said stationary member and adjustable circumferentially about the same, said inner thread guide being pivotally supported on said collar whereby said thread guide may be swung from beneath the overhanging portion for threading, a

85 yielding spring arm having a projection 90 adapted to engage a recess in the support for the inner thread guide for holding said thread guide in normal position beneath the overhanging portion.

95 10. A thread controlling mechanism for sewing machines including a rotating thread controlling member having a laterally projecting thread engaging surface overhanging the axis of rotation of said member, thread

100 guides located one within and the other without said overhanging portion, a stationary member mounted coaxially with said controlling member, a split collar supporting said thread guides and mounted on

105 said stationary member and adjustable circumferentially about the same, said inner thread guide being pivotally supported on said collar whereby said thread guide may be swung from beneath the overhanging portion for threading, a cast-off and retainer associated with said thread controlling member,

110 a collar carrying said cast-off and retainer mounted on said stationary member for adjusting the cast-off and retainer circumferentially about the axis of rotation independently of the adjustments of the split collar carrying the thread guides.

115 11. A thread controlling mechanism for sewing machines including a rotatable shaft, a thread controlling member mounted on said

120 shaft and having a laterally projecting thread engaging surface overhanging the shaft, a stationary sleeve surrounding the shaft and extending beneath said overhanging portion, thread guides located one within

and the other without said overhanging portion, a split collar mounted on said sleeve and carrying said thread guides, said split collar being circumferentially adjustable about said sleeve, a cast-off and retainer associated with said thread controlling member, a collar carrying said cast-off and retainer independently mounted on said sleeve for circumferential adjustment.

10. In testimony whereof, I affix my signature.
JOSEPH BERGER.
